UNITED STATES PATENT OFFICE

CHRISTIAN KONOLD, OF VERONA, PENNSYLVANIA, ASSIGNOR TO CREEPCHECK COMPANY, INC., OF NEW YORK, N. Y., A CORPORATION OF NEW YORK

RAIL ANCHOR

Application filed August 30, 1927. Serial No. 216,387.

This invention relates to rail anchors and more particularly to one piece or unit anchors.

An object of this invention is to provide a one piece or unit rail anchor capable of use 5 with rails having bases of different dimensions.

While the patent to Dinklage, No. 1,527,427, shows a one piece rail anchor adapted to engage the bottom portion of a track 10 rail adjacent a tie member for checking the creep of the rail nevertheless the structure shown by this patent does not provide means for adjusting the grip of the anchor upon a rail base.

Another object of this invention is to provide a one piece or unit rail anchor the rail 15 base grip of which may be adjusted.

These and other objects which will be apparent to those skilled in this art are attained 20 by means of the device hereinafter described and claimed and illustrated in the accompanying drawings.

In the drawings, Figure 1 is a side elevational view of a rail anchor embodying the invention shown applied to a rail.

Fig. 2 is a view similar to Fig. 1 showing the anchor of Fig. 1 applied to a rail having a narrower base and,

Fig. 3 is a view similar to Figs. 1 and 2 but showing a modification of this invention.

The anchor of this invention is shown applied to a rail having a web 11 and a base 12 with edges 13 and 14 for such base.

The anchor is made from a single piece of metal preferably steel of the proper carbon content and preferably from bar stock. One end of the anchor 15 is formed in a shape of a hook 17 the inner faces of which form a jaw 18 for cooperating with the edge 14 of the rail 11. The jaw 18 is of sufficient depth to engage an appreciable portion of the rail edge 14 to prevent damage to the edge 14. The remaining portion 19 of the anchor 15 is bent downwardly and away from the base of the rail and terminates in an upwardly extending portion 21.

Upon moving the portion 21 in an upward 50 direction the top face of the curved portion

22 will come in contact with the lower face 23 of the rail base 12 and act as a fulcrum.

The means 16 which is disposed on the right face of the upwardly extending portion 21 comprises a plurality of projections 24 which are adapted to cooperate with the edge 13 of 55 the rail 11. The spaces between the projections 24 provide jaws or seats for receiving the edge 13 of the rail 11 and cause the anchor 15 to tightly grip the base 12. The portion 21 is provided with a cam surface 25 for preliminarily engaging the edge 13 and guiding the anchor upwardly until the top portion of the edge 13 passes under the desired extension 24, the resiliency of the anchor 15 serving to firmly hold the same in proper contact with 60 base 12, see Figs. 1 and 2.

In applying the anchor to the rail the hook portion 17 is first placed over the face 14 of the rail 11 and a suitable tool is used for exerting upward pressure on the portion 19 which will tend to slightly straighten the anchor 15 causing the portion 21 to move upwardly until the top portion of the edge 13 of the rail 11 comes into engagement with the 65 lower portion of the desired projection 24.

The portion 19 of the anchor 15 extends downwardly a considerable distance from the bottom face 23 of the rail 12 thereby providing ample surface for cooperation with the tie 26 as is shown by Fig. 1.

Referring particularly to Fig. 3 in which I illustrate a modification of the means for permitting adjustment of the anchor to rails having bases of different widths. I provide a 70 plurality of projections 26, 27, 28, etc., or an irregular surface which would constitute a plurality of projections for cooperating with the edge 13 of the rail 11. The distance between the uppermost projection 26 and the inner face of the groove or slot 18 on the opposing side of the anchor 15 is greater than the distance between the projection 27 and the inner face of the slot or groove 18, and so on. The distance between the lowermost projection 28 and the inner face of the slot 18 is shorter than any of the distances between either of the projections 26 or 27 and the inner face of the slot or groove 18.

In addition to the distances just mentioned 100

becoming shorter between the projections and the inner face of the jaw 18 the gripping power of the anchor 15 is increased as the portion 21 is moved upward.

5 It can be seen from the above description that I have provided a one piece or unitary rail anchor which can be adjusted to rails having bases of different widths so as to have substantially the same holding power on these 10 rails.

It will be observed that it is essential in carrying out my invention that, whether there are two humps 24, 24, as shown in Figs. 1 and 2, or three humps, as shown in Fig. 3, the 15 inner surface of the upstanding member 21, at a point below the cam face 25, shall be substantially serpentine in shape, so that the upper rounded surfaces of the lower hump or humps shall serve as cam surfaces, in the 20 manner of the cam surface 25, so as to assist in springing the upstanding member outwardly far enough to engage the upper corner of the rail edge under the lower hump.

While I have illustrated and described but 25 one embodiment of this invention it will be apparent to those skilled in the art that certain changes, modifications, substitutions, additions and omissions may be made in the device without departing from the spirit and 30 scope of the appended claims.

What I claim as new and desire to secure 35 by Letters Patent is:

1. A rail anchor comprising a resilient yoke with one face adapted to lie against the tie 35 and having a hump which when the anchor is in operative position contacts with the bottom of the rail-base to form a fulcrum, a jaw at one end for engaging one edge of the rail-base, and a springy upstanding end-portion 40 at the other end whose inner face is adapted to engage the other edge of the rail when in operative position, said inner face having a substantially serpentine formation to provide a plurality of rounded humps any 45 one of which is adapted to engage over the upper corner of the rail-edge to lock the anchor to the rail, for the purpose set forth.

2. A one piece rail anchor having a hook end adapted to receive one side of a rail flange 50 and an oppositely located upstanding end adapted to engage the other side of the rail flange, the upstanding end having a cam face for preliminary engagement with the rail flange for spreading the upstanding end away 55 from the hook end, the last named end having a plurality of rail seating recesses, the distance between each of the recesses and the opposite end of the anchor being different to afford means for positively locking the anchor to different width of rails.

3. A one piece rail anchor having a hook end adapted to receive one side of a rail flange and an oppositely located upstanding end adapted to engage the other side of the 60 rail flange, the last named end having a plu-

rality of rail receiving recesses, the distance between each of the recesses and the hook end of the anchor being different to afford means for positively locking the anchor to different width rails and the opposite ends being connected by a bowed yoke to permit them to be sprung apart in applying the anchor, at least one of said recesses having sides bearing on both the top and bottom of the rail flange. 70

In testimony whereof, I have hereunto subscribed my name this 29th day of August, 1927.

CHRISTIAN KONOLD.
